LUGGAGE LOCK

Steven S. Feinberg, 28 Linden Drive,
Providence, R.I. 02906

Filed Mar. 25, 1968, Ser. No. 11,108

Term of patent 14 years

Int. Cl. D8—03

U.S. Cl. D8—129

FIG. 1

FIG. 2

FIG. 3

FIG. 1 is a plan view of my new design in locked position.

FIG. 2 is a side view of my new design in locked position.

FIG. 3 is a side view of my new design in unlocked position.

FIG. 4 is a slightly enlarged perspective view of my new design in locked position.

The dominant features reside in the solid line portions. The broken lines of a portion of a luggage case are for illustrative purposes only.

I claim:

The ornamental design for a luggage lock, as shown and described.
